FIG. 2

FIG. 3

FIG. 4

FIG. 5

FIG. 1 is a perspective view of an ice cream freezer container showing my new design, the broken line illustration in this view only being for illustrative purposes to indicate environmental use;

FIG. 2 is a top plan view of the ice cream freezer container shown in FIG. 1;

FIG. 3 is a left side elevational view thereof;

FIG. 4 is a front elevational view thereof; and

FIG. 5 is a right side elevational view thereof.

The characteristic feature of the design resides in the pattern on the sides of the ice cream freezer container.

I claim:

The ornamental design for an ice cream freezer container, as shown and described.
